INVENTOR.

George H. Magrath

BY Oscar L. Owen

ATTORNEY.

UNITED STATES PATENT OFFICE.

GEORGE H. MAGRATH, OF WHITINSVILLE, MASSACHUSETTS, ASSIGNOR TO WHITIN MACHINE WORKS, OF WHITINSVILLE, MASSACHUSETTS.

THREAD GUIDE FOR SPINNING AND TWISTING MACHINES.

Application filed April 1, 1927. Serial No. 180,118.

My invention has reference to thread guides for spinning and twisting machines; and it consists in certain improvements set forth in the following specification and 5 shown in the accompanying drawings, which form part thereof.

Heretofore a thread guide has been formed of a solid block of porcelain, glass or metal supported in a holder which is usually adjustably mounted on the framing of the 10 machine. In a guide of this type frequent breakages of the guide block occur necessitating the replacement with a new block at a considerable expense.

15 The object of my invention is to provide a simple construction of the thread guide and holder thereof which shall embody cheapness, durability, adaptability and adjustability.

20 The novel features of my invention are fully described in the following specification and claims and illustrated in the accompanying drawings in which:

Figures 1 to 3 inclusive illustrate a section 25 of my improved guide, Figure 1 being a plan, Figure 2 a side view and Figure 3 an end elevation. Figures 4, 5 and 6 illustrate respectively the plan, side and end views of an assembled guide made up of 30 two individual duplicate sections in a reversed relation with each other. Figure 7 is a perspective view of my guide holder. Figure 8 is a perspective view of the clamp for maintaining the guide in its holder.

35 Figure 9 is a plan of the assembled guide in its holder showing the manner of attaching the holder to the thread board of a twisting machine. Figure 10 is an end view of the guide in its holder showing 40 the diagonal path for the thread into the eye of the guide, and Figure 11 is a sectional view on line 11—11 of Figure 9.

Throughout the following detailed description, and on the several figures of the drawings, similar parts are referred to by like 45 numeral characters.

My improved guide consists of a block shown in Figure 4 made up of a pair of 50 duplicate sections (shown in Figure 1) which may be made of porcelain or other suitable material with smooth polished surfaces. Each section has a flat body portion, the rear end 12 of which serves as a base adapted to register with the base of the

other section in the formation of the guide 55 block. The front end 13 of the body is hooked shaped for retaining the thread in its guide eye 14 located in the center of the body portion. A narrow lateral slit 15 opens into the side of the eye to allow 60 for the insertion of the thread. The side of the hooked portion of the body opposite of the slit 15 is provided with a flange 16 projecting at right angles thereto, the inner side of the flange being bevelled towards the point of the thread retaining hook 13, thus providing a diagonal passage 65 for the thread into the slit of the guide eye.

The guide block is formed by placing a 70 pair of sections in reversed position together so that both bases 12 and guide eyes 14 register with each other respectively and the hooked portions 13 overlap each other leaving a diagonal path 17 between for the 75 insertion of a thread into the guide eye.

The block is then placed in the box-end 18 of the sheet metal holder 19 and tightly held therein by a clamping member 20 fastened to the underside of the holder 19 80 by a bolt 21 and locking nut 22. The holder 19 is adjustably mounted on the thread board 23 fixed to the framing of the machine.

I claim—

1. A thread guide comprising a pair of 85 separable duplicate sections, each section having a rear base portion, a hook shaped front portion forming a guide eye between said portions with a slit opening into one 90 side of said eye, a flange projecting at a right angle from said hook shaped portion, the inner side of said flange being bevelled towards the point of the hook, said sections formed into a block by combining them together in a reversed relation with each other with the base and eye on one section registering respectively with those of the other, and means for holding the sections together in a block formation.

2. A thread guide comprising a pair of 100 separable duplicate sections, each section having a rear base portion, a hook shaped front portion forming a guide eye between said portions with a slit opening into one 105 side of said eye, a flange projecting at a right angle from said hook shaped portion, the inner side of said flange being bevelled

towards the point of the hook, said sections formed into a block by combining them together in a reversed relation with each other with the base and eye of one section registering respectively with those of the other, a sheet metal holder having a chamber therein for the reception of said block, a sheet

metal member bolted to the holder for maintaining the block in the chamber, and means for adjustably mounting the holder on the 10 thread board.

In testimony whereof, I have signed this specification.

GEORGE H. MAGRATH.
